UNITED STATES PATENT OFFICE.

EDWIN W. LUCE, OF BRADFORD, PENNSYLVANIA.

GAGE-COCK.

SPECIFICATION forming part of Letters Patent No. 425,441, dated April 15, 1890.

Application filed June 25, 1889. Serial No. 315,472. (No model.)

To all whom it may concern:

Be it known that I, EDWIN W. LUCE, a citizen of the United States, residing at Bradford, in the county of McKean and State of Pennsylvania, have invented certain new and useful Improvements in Gage-Cocks; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention is in the nature of an improvement in a gage-cock for steam-boilers, and has for its object to generally improve this class of devices and render them more easy to clean and repair while under pressure without the necessity of cooling off the boiler so as to remove them for such purposes.

With this object in view my invention consists in the improved construction, arrangement, and combination of parts hereinafter 20 fully described, and afterward specifically pointed out in the claims.

I will now proceed to describe my invention, having reference to the accompanying drawings, in which—

30 Figure 1 is a view showing a gage-cock constructed in accordance with my invention, the parts, except the handle, being shown in vertical section. Fig. 2 is a detail view showing the upper screw-plug and the screw-cap (which, together with the packing, form the 35 stuffing-box) in side elevation removed from the cock and slightly separated; and Fig. 3 is a detail view showing the interior mechanism of the cock, partly in section and partly 40 in elevation, removed from the cock and slightly removed from their normal relative positions.

Like letters of reference mark the same parts wherever they occur in the various figures of the drawings.

45 Referring to the drawings by letter, A is the body of the cock. It is provided with a screw-threaded stem B for attachment to the boiler, bored to permit the passage of the 50 steam or water therefrom, as at C. It is further provided with the main body D, vertically bored at E, having an interior thread F

at the top, another interior thread G at the bottom, and an annular inward-projecting flange H about midway its length. The bore 55 E of the body lies at a right angle to and communicates with the bore C of the stem, and is divided by the flange H into an upper chamber I and a lower chamber J. A screw-plug K engages the upper thread F and has 60 an annular flange which fits tight against the top of the body D, a packing-ring being interposed if thought desirable. This plug is centrally bored, said bore being interiorly threaded at its lower end. The upper end of 65 this bore is larger than the rest, leaving space for a tubular gasket L, preferably of soft metal. The lower end of this space is enlarged by being angularly undercut at M, the bottom of said under-cut being inclined downward and inward, as at N. When the gasket 70 is inserted, its interior forms a continuation of the lower part of the bore, and within it is placed the stem O of a cup-shaped valve P, having a removable handle Q at its top. 75 Around this valve-stem screws a screw-cap R, having a central downward-projecting flange S, which fits into the enlarged upper part of the bore of the plug K and upon the top of the gasket L. The stem O is also bored 80 centrally from the bottom, but partially through and a spiral or other spring T secured therein. Within this bore is also placed the upper end of the stem U of another cup-shaped valve V, which has a continuation at 85 W below the cup.

In the lower thread G of the bore E is secured a plug X, which is centrally bored at Y, and has an upward-projecting tubular flange Z at its top. This bore is constricted 90 at its lower end so that the lower end of the stem W fits closely therein, while an annular chamber a is formed around the stem above. The stem W is provided with a transverse slot b, which opens at each end into said chamber a, and communicates at its center with the lower central bore c of said stem, said bore c extending to the lower end of the stem.

An annular soft-metal gasket d, angular or 100 L-shaped in cross-section, rests upon the upper end of plug X, and is inclosed, except its upper side, by said plug, its annular upright flange Z, and the body D, with its annular

inward-projecting flange H, hereinbefore described. The exposed upper face of the gasket d forms the seat for the edge of the cup-shaped valve V.

5. The lower end of the bored stem W is made smaller than the main body thereof, as at e, forming an annular inverted shoulder f.

On the side of the main body of the valve opposite to the stem B are formed two ears or

10 lugs g, between which is pivoted a handle N, whose inner end i rests under a projecting head j of an L-shaped bar k. The horizontal arm of the bar k passes under the main body of the cock, and is passed up over the lower end e of stem W, resting against shoulder f, said lower end e passing through a hole in the said horizontal arm of the L-shaped bar k. A stop l between the lugs g serves to limit the downward movement of the inner end i 15 of handle h.

20 The operation of my invention may be described as follows: The stem being screwed into the boiler, the steam therefrom will enter the chamber I through bore C. Plug K will prevent its passage therefrom upward, while the flange H and cup-shaped valve V will prevent its passage downward, so that there will be no escape of steam, the cup-valve V being held to its seat on gasket d by the 25 pressure of the steam, in addition to the force of spring T on top of its stem U. If, however, the handle h is moved downward, its inner end i will raise the L-shaped bar k, and this, by pushing upward on shoulder f of stem 30 W, will raise the valve V off its seat, thus allowing the steam to escape from chamber G through slots b and bore c of stem W to the outer air. When the handle is raised, (which will be done when it is released by the action 35 of spring T through the medium of stem W, shoulder f, and bar k,) the valve V will again rest on its seat f, thus cutting off the escape 40 of the steam. When it is desired to remove the interior parts of the cock from spring T 45 down for repairs or replacement, the cup-valve P is screwed down until it engages the flange H, thus effectually closing chamber I. Now, by lowering the inner end of the handle the bar k may be slipped off the end e of stem W 50 and removed. The plug X may now be removed and all the parts taken out.

55 The angular soft-metal gasket d, being confined on all sides by hard metal, cannot be spread or mashed out of shape, and is also by that arrangement almost wholly protected from the destroying action of the steam or water passing through the cock.

60 The valve V would generally drop by gravity to its seat upon removing the upward pressure of bar k; but should there be any

tendency to stick, the force of gravity will be supplemented by the action of spring T.

The shape of the cavity in which the sleeve-gasket L is confined is such that downward pressure upon its upper edge by flange S of 65 cap R will cause its lower end to tightly inclose the stem O of valve P and thus preserve a tight joint, while the gasket will also be prevented from spreading.

The provision of the removable handle Q 70 permits the removal of the upper interior parts of the cock (being plug K, gasket L, and cap R) whenever desired, which would not be possible were the handle rigidly secured to the stem. 75

Having thus fully described my invention, what I claim, and desire to secure by Letters Patent of the United States, is—

1. The combination, with the body of the cock having an annular inward-projecting 80 flange, of a cup-shaped valve having a bearing thereon, a second cup-valve within the first having a bored stem projecting downward and reaching outside the cock, a screw-plug through which said stem passes, and a 85 gasket resting upon said plug and forming a seat for the second cup-valve, as set forth.

2. The combination of the body of the valve having bored stem entering the boiler, inward-projecting flange H, chambers E and I, 90 and closed upper end, with cup-shaped valve V, having bored and slotted stem W, as set forth.

3. In combination, the valve V, having bored stem communicating with chamber I 95 when said valve is raised, the L-shaped bar k, having head P, and the handle h, whose inner end engages with said head, as set forth.

4. In combination with the body of the valve and its plugs K and X, the inner cup-valve, its stem, the outer cup-valve, its stem bored to receive the stem of the inner valve, and the spring in said stem to supplement the action of gravity upon the inner valve-stem, as set forth. 105

5. In combination, the body of the valve, the screw-plug X in the lower end, having a bore smaller at the bottom than the top, and the valve V, having stem W, with bore c and slots b, said slots opening communication between the bore c and the chamber a, formed by enlarging the upper part of the bore of the screw-plug, as set forth. 110

In testimony whereof I affix my signature in presence of two witnesses.

EDWIN W. LUCE.
